CLAIM

The ornamental design for an animal harness as shown and described.

DESCRIPTION

FIG. 1 is a perspective view of an animal harness showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof.

FIG. 8 is another perspective view of the animal harness showing our new design being worn by a dog;

FIG. 9 is a front view thereof;

FIG. 10 is a left-side view thereof;

FIG. 11 is a right-side view thereof; and

FIG. 12 is a top view thereof.

FIG. 13 is a front view of the animal harness showing our new design in a flat configuration;

FIG. 14 is a rear view thereof;

FIG. 15 is a right-side view thereof;

FIG. 16 is a left-side view thereof;

FIG. 17 is a top view thereof; and

FIG. 18 is a bottom view thereof.

The broken-lines outline of a dog in FIGS. 8-12 represent environmental subject matter that forms no part of the claim. The remaining broken lines shown in the drawings represent portions of the animal harness that form no part of the claimed design.
